UNITED STATES PATENT OFFICE.

WILLIAM DE FREITAS, OF NEW YORK, N. Y., ASSIGNOR TO CONSOLIDATED GAS COMPANY, OF NEW YORK, N. Y., A CORPORATION OF NEW YORK.

GAS-BURNER SUPPORT.

SPECIFICATION forming part of Letters Patent No. 783,181, dated February 21, 1905.

Application filed January 16, 1904. Serial No. 189,224.

To all whom it may concern:

Be it known that I, WILLIAM DE FREITAS, a resident of the city, county, and State of New York, have invented certain new and useful 5 Improvements in Gas-Burner Supports, of which the following is a full, clear, and concise specification.

The object of the present invention is to provide a simple durable construction whereby 10 the burners of gas-ranges, and more particularly the oven-burners of the same, may be readily removed for cleaning, &c., and whereby also their operating and controlling mechanisms may be conveniently interchanged 15 from one side of the range to the other to permit of the range being installed in any position in a room, with the gas-controlling valves and pilot-light located in the most convenient and accessible position with respect to 20 the range.

In prior gas-ranges of which I am aware the oven-burners have had their gas-supply cocks and pilot-light permanently located on one or the other side of the range, which requires 25 frequently that the range be disassembled or exchanged for another when the desired and most convenient position in the room happens to be one in which a wall or other object obstructs access to the valves. These difficulties are entirely overcome by the present invention, according to which the brackets or plates, which may constitute the sole supporting means for the burners, are quickly interchangeable from one side to the other and the 30 gas-supply valves, together with the pilot, thus moved from right to left, and vice versa, without disassembling the range or requiring a great amount of time or skill; and, furthermore, the embodiment of this invention is such 35 that the burners themselves may be quickly removed from the range and replaced by unskilled persons by simply lifting one end and withdrawing the burner from the compartment.

40 Reference is made to the accompanying two sheets of drawings, which form a part of this specification, and in which—

Figure 1 is a side elevation of one of the burner-supporting plates as viewed from the

interior of the burner-compartment, the side 50 walls of said compartment being shown broken away. Fig. 2 is a top plan view of Fig. 1. Fig. 3 is an end elevation of one of the burners proper. Fig. 4 is a top plan, partly in section, of the supporting-plate for the open ends 55 of the burner and the pilot. Fig. 5 is a detail, and Fig. 6 is a transverse sectional view, of a burner-compartment with the plates and burners in position.

The opposite side walls of the burner-compartment are provided with apertures or openings 1, preferably disposed opposite each other and of the same shape and size, and each aperture is preferably, though not necessarily, provided with a slot 2 at one end for receiving a lug 3, formed on each of the plates 8 and 18, Fig. 6, which are adapted to be secured as interchangeable covers to the openings. The burners 4 are tubular perforated bodies having their closed ends reduced or formed with feathered projecting pins 5 and their other ends enlarged to form a bell-shaped gas-receiving end or mouth 6 with its rim 7 slightly turned inwardly, as shown, so that it will fit and be easily seated in an end socket in the plate 8, which is 70 the one located upon the valve-controlling side of the range. The plate 8 is of a single piece or casting, as shown, and is provided at one end with an offset flange 9, having the projecting lug 3 formed upon it, so that when the flange 75 is inserted behind the end of the opening 1 the lug will enter the slot 2, and thereby hold the plate rigidly clamped upon the outside of the compartment-wall, completely covering the opening. The other end of the plate is provided with a similar flange; but it is adapted to rest upon the outside of the wall and be clamped thereagainst by means of a single 80 stove-bolt 10, as shown. It is obvious that by this form of construction the plate 8 may 85 be quickly disconnected from one side wall and secured to the other by simply loosening the bolt 10 and unseating the flange and lug 3. The body portion of the plate 8 is provided with one or more depressions or sockets 11, 90 of which there may be any desired number, opening horizontally and inwardly and forming end seats for holding the open bell-

mouths of the burners, as above described. The range is connected with the gas-main at a point 15 in the rear, and a pipe 16 leads from thence and is supported parallel to the plate 8, with a gas-cock projecting from it opposite each socket, the free ends or nozzles 17 of the cocks passing through suitable central openings in the sockets 11, so as to be capable of directing a jet of gas centrally into the burners 4. Each socket is also provided with a series of apertures 12 for admitting air to the burner, and a perforated cover-plate 12' is adjustably mounted upon the outside of the plate, whereby the amount of air admitted 15 may be regulated in the usual manner. In the middle of the plate, or, if there are more than one socket, between each pair of sockets, there is formed a passage 13, preferably with an inwardly-projecting neck, as shown, for holding the pilot-light 14. The latter is of the usual construction, and its tube is passed through the aperture 13, where it is secured to one of the nozzles, as shown.

The open or gas-receiving end of the burner 25 forms, in conjunction with the socket 11, a chamber in which gas from the inlet 17 and air from the passages 12 are mixed, and the rim 7 of the bell-mouth is formed to fit rather snugly in the socket, so as to exclude air from 30 the chamber, except from the passages 12, where the supply may be regulated.

The closed ends of the burners are supported by a plate 18, Figs. 1 and 2, which is of the same size and marginal construction as the 35 plate 8, so that it may be secured interchangeably in either of the apertures 1 of the side walls, as above described. The inner side of the plate is provided with a set of projecting lugs 19, forming a seat for a yoke-piece 20, 40 permanently secured therein by means of the bolts shown. In the case of a construction involving only two burners the ends of this yoke-piece are provided with suitable sockets opening upwardly to receive the pins 5, and 45 the bottom of each socket or seat 21 is grooved or slotted to register with the feather 22 on the end pin 5, the purpose of the feather and groove being to insure that the perforations in the burner will be held in the proper position to direct the flames in the desired directions. Where several burners are supported by the plates, sockets may obviously be formed at intervals intermediate of its ends. The plates 8 and 18 being thus of identical 55 marginal size and construction are capable of fitting with equal facility into either of the openings 1 in the side walls of the burner-chamber, and inasmuch as the burners are supported entirely by them it follows that the 60 controlling mechanism may be disposed upon any side of the range upon which there is an aperture. A change from one side to the other involves simply a removal of the burners, which is accomplished by lifting the pins 5 65 from their seats and withdrawing the bell-

mouths from the end sockets 11, disconnecting the supply-pipe 16, and withdrawing the nozzles from the plate, whereupon both the plates may be unbolted and interchanged and the gas-supply cocks mounted on the other side. It will be observed that both plates 8 and 18 are secured to and removable from the outside of the range by manipulating a single bolt, thereby obviating the difficulties usually encountered in ordinary ranges where bolts 75 and screws must be unfastened from the inside of an oven or a warming-closet. The pilot-light while easily separable from the plate 8 by loosening the screw 23 will be more conveniently left within the plate 8 during the 80 interchange.

While I have described and illustrated my invention as applicable to oven-burners, it is manifest that it is equally serviceable in other forms and kinds of burners, and I wish it to 85 be understood that the mixing-chamber may be formed wholly within the end of the burner, if desired, and that the style and shape of the burners and plates may be varied in many respects without departing from the spirit and 90 scope of my invention.

Having described my invention, what I claim, and desire to secure by Letters Patent of the United States, is—

1. A gas-range, comprising a burner-compartment provided with apertures therein and a burner supported by its ends in said compartment, in combination with plates mounted on the exterior of said compartment supporting said burner through the apertures. 95

2. A gas-range, comprising a burner-compartment having apertures and a burner within said compartment, in combination with removable plates closing said apertures from the exterior and a seat on one of said plates protruding within the compartment to form a support for one end of the burner. 105

3. A gas-range comprising a burner-compartment having apertures in the walls thereof, a burner in said compartment and plates adapted to cover said apertures interchangeably, provided with means for supporting said burner. 110

4. A gas-range comprising a burner-compartment having apertures of similar shape in the walls thereof, a burner in said compartment, a pair of plates having marginal formations to fit either of said apertures and respectively formed to support the opposite ends of said burner. 115

5. A gas-range comprising a burner-compartment having apertures in the walls thereof, a burner in said compartment having a closed and an open end, in combination with a pair of outside plates respectively adapted 125 to fit and support the said ends and having appropriate formation to cover either of said apertures interchangeably.

6. A gas-range comprising a pair of apertures of similar shape and a burner provided 130

with an open end, a pair of plates adapted to fit either of said apertures interchangeably, one of said plates being provided with a seat for supporting the open end of the burner and formed to constitute an air and gas mixing chamber in conjunction therewith.

7. A gas-range, comprising a burner-compartment and a burner extending horizontally across the same, in combination with plates on the exterior of said compartment, one of said plates being provided with a socket opening horizontally to receive one end of the burner and the other being provided with a socket opening vertically to receive the other end of the burner.

8. The combination in a gas-range of a burner-compartment provided with an aperture in the wall thereof and a burner-support comprising a plate covering said aperture and provided with an offset flange at one end to engage and clamp against the opposite side of the wall and means at the other end of said plate for fastening the same to said wall.

9. A gas-range comprising a burner-compartment and a burner therein, apertures in the walls of said compartment and interchangeable plates for covering said apertures, one of said plates being provided with means forming a gas-mixing chamber for one end of the burner and the other being adapted to receive the other end of the burner.

10. In a gas-range, a burner-compartment having an aperture in the wall thereof and a removable cover-plate therefor, an offset flange on one end of said plate to engage with the margin of said aperture and a lug on said flange to engage in a slot in the said margin, in combination with means at the other end

of said cover-plate to fasten it to the compartment-wall and a burner supported by said plate.

11. In a gas-range, the combination of a burner-compartment having an aperture in the wall thereof, a plate removably secured to said wall, covering the aperture and provided with an inwardly-projecting portion, and a part adapted to support a burner end secured to said inwardly-projecting portion.

12. In a gas-range, the combination of a burner-compartment having an aperture, a plate covering said aperture formed with sockets opening inwardly to form burner end seats and being also formed with a passage between pairs of sockets to receive a pilot-light.

13. In a gas-range, a support for the end of a burner consisting of a cover-plate adapted to be secured to the exterior of a burner-compartment and provided with a socket to receive said burner, in combination with a tubular neck formed on said plate adjacent said socket for supporting a pilot-light.

14. A gas-range, comprising a burner-compartment and a burner supported by its ends therein, in combination with a supporting means for said burner permitting the reversal of the position of the same within the compartment and means for connecting said burner with a gas-main in either position, substantially as described.

In testimony whereof I have signed my name to the specification in the presence of two subscribing witnesses.
